UNITED STATES PATENT OFFICE.

EDWIN H. SMYTHE, OF CHICAGO, ILLINOIS, ASSIGNOR TO WESTERN ELECTRIC COMPANY, INCORPORATED, OF NEW YORK, N. Y., A CORPORATION OF NEW YORK.

TELEPHONE APPARATUS.

Application filed November 5, 1925. Serial No. 66,951.

This invention relates to acoustic devices, and particularly to sound transmitting and reproducing devices employing large direct-acting diaphragms.

5 The object of the invention is to provide means for automatically maintaining the adjustment of sound reproducing devices regardless of any permanent or temporary displacement of the center of the diaphragm 10 due to contraction or expansion of materials, or to any other cause.

In accordance with the present invention a telephone sound transmitting or reproducing device of the loud speaking type is provided with means for maintaining a constant relation between the center of the diaphragm and the electro-responsive element regardless of any change in shape or dimensions of its members due for example to their 20 contraction and expansion under variations in humidity and temperature.

In one arrangement a magnetic unit which has a large mass and preferably of the biased armature type is supported on vertical pivots remote from its center of the mass so as to offer high impedance and remain substantially rigid to vibrations at frequencies of importance in music and speech and still move readily with the center of the 30 diaphragm when the diaphragm is deflected by permanent or temporary forces such as are caused by its contraction and expansion. The pivots may be adjusted to give any desired degree of resistance depending upon 35 the size, the shape and the material of the diaphragm and the mass of the magnetic unit. In any case they may be set up quite tight as equilibrium of the static forces will be established immediately upon the operation 40 of the device.

Referring to the drawings Fig. 1 is a plan view of a loud speaker embodying the invention, the diaphragm being broken away to show the magnetic unit; Fig. 2 is a detail 45 side view of the magnetic unit of the invention; and Fig. 3 is a front view of the magnetic unit.

For the purpose of illustration the invention is shown applied to a loud speaking receiver of the cone type such as described and claimed in application Serial No. 690,803, filed February 5, 1924, for G. W. Burchett, wherein 5 represents the mounting for a double conical diaphragm 6 and the electro-

magnetic driving unit 7 which is connected 55 to the apex of the diaphragm by a rod 8.

A bracket 9 attached to the support 5 at three points by any suitable means, such as screws 10, carries two parallel projecting lugs 11 and 12, each of which is threaded to 60 receive bearing screws 13 and 14, respectively. The magnetic system may be of any well-known type having an armature balanced or biased such as that disclosed in R. L. Wegel application Serial No. 635,407, filed April 30, 1923 or patent 1,365,898 of January 18, 1921 to H. C. Egerton. A bar 16 provided with parallel ends 18 and 19 is secured to the magnet 15 at a point remote from the center of mass of the unit by a 70 strap 20 and a screw 21. The ends 18 and 19 of the bar 16 are provided with recesses which engage the ends of the bearing screws 13 and 14, respectively. These recesses are preferably hemispherical and the 75 ends of the screws 13 and 14 are correspondingly shaped so as to provide a large bearing surface for introducing friction. The bar 16 may be made of resilient material so as to facilitate in adjusting and maintaining 80 the pressure on the pivots. Lock nuts 22 and 23 are provided for the pivot screws 13 and 14 for locking them after adjustment.

As in case of the receiver disclosed in the R. L. Wegel application Serial No. 635,407, filed April 30, 1923, to the poles of the magnet are attached pole pieces 26 and 28 between which an armature is supported at its mid-point by a resilient reed not shown. A lever 24 is secured to the pole piece by a 90 screw 27 and its free end is connected to one end of the armature by a rod 25. At a point intermediate the ends of the lever the diaphragm 6 is connected by the rod 8.

For the purpose of limiting the maximum movement of the magnet a screw 30 which secures one of the pole pieces to the magnet is extended through a hole 31 in the bracket 9 and the end is provided with nuts 34 which act as stops. In shipping the unit 100 these nuts may be turned down so as to rigidly secure the magnet to the bracket. Under operating conditions the clearance 105 between the stop nuts and the frame should be such as to permit maximum movement due to the contraction and expansion of the diaphragm under changes of temperature and humidity.

This provides a convenient arrangement for automatically compensating for the contraction and the expansion and any permanent or temporary displacement of the diaphragm and insures permanent adjustment of the air gap between the armature and the pole pieces which is essential for the proper operation of sound reproducing devices. The magnetic system being quite massive and supported at a point remote from its center of mass offers a very high impedance to vibrations at frequencies of importance in sound and speech reproduction. The friction at the pivots adds to this impedance in maintaining adjustment of the air gap. Since the axis of the pivots is vertical, any displacement of the magnetic unit introduces no stresses in the vibratory system. Should any stresses set up by the expansion or the contraction of the diaphragm be insufficient to overcome the friction of the pivots, a state of equilibrium will be established as soon as operating current is applied and the diaphragm starts operating.

25 What is claimed is:

1. In a loud speaking receiver having an actuating device of large mass, a large direct-acting diaphragm operatively associated with said actuating device and a support for said device, means connecting said device and said support to permit relative movement therebetween whereby the operation of the device is unaffected by expansion and contraction of the diaphragm.
2. In a loud speaking receiver, a sound radiating member, an actuating member, a support for said members, and means intermediate one of said members and said support maintaining the adjustment of said actuating member independent of the changes in shape of said radiating member.
3. In a loud speaking receiver, having a diaphragm, a balanced armature in operative relation to said diaphragm, a magnet and a support and means intermediate said support and said magnet maintaining the balance of said armature independent of the changes in shape of said diaphragm.
4. In an acoustic device, having a large

conical diaphragm, a magnetic unit for driving said diaphragm, and a support for said unit, a pivotal connection between said support and unit, said connection being remote from the center of mass of said unit.

5. In a sound reproducing device, having a diaphragm, an electromagnet, and a support common to said diaphragm and said electromagnet means interposed between said electromagnet and said support for supporting said electromagnet for movement in a horizontal plane and maintaining the adjustment of said unit under changes in shape or dimensions of said diaphragm.

6. In a loud speaking receiver, a large direct-acting conical diaphragm, a magnet having an armature and pole pieces in spaced relation, means for maintaining a spaced relation between said armature and pole pieces under the contraction and expansion of said diaphragm due to changes in humidity and temperature, said means comprising pivots supporting said magnet for movement in a horizontal plane.

7. In a sound reproducing device having a large direct-acting diaphragm, an actuating device and a support common to both, means of securing said operating means at a point remote from its center of mass to said support for relative movement thereof in a horizontal plane whereby stresses due to the contraction and expansion of said diaphragm are relieved by the displacement of said actuating device.

8. A sound reproducing device comprising a large direct-acting diaphragm, a permanent magnet, a support common to said diaphragm and said magnet and vertical friction pivots remote from the center of said magnet connecting it to said magnet, an armature, means resiliently supporting said armature in operative relation to said pole pieces, and means connecting said armature to said diaphragm.

In witness whereof, I hereunto subscribe my name this 30th day of October A. D., 1925.

EDWIN H. SMYTHE.
